UNITED STATES PATENT OFFICE

165,699

ELECTRIC MEAT, FISH, AND BONE CUTTER

Arnold C. Schueren, Chicago, Ill., assignor to
Vaughan Company, Chicago, Ill., a corporation
of Illinois

Application March 7, 1950, Serial No. 8,375

Term of patent 14 years

(Cl. D55—1)

To all whom it may concern:

Be it known that I, Arnold C. Schueren, a citizen of the United States, residing at Chicago, in the county of Cook and State of Illinois, have invented a new, original, and ornamental Design for an Electric Meat, Fish and Bone Cutter, of which the following is a specification, reference being had to the accompanying drawings, forming a part thereof.

In the drawings:

Figure 1 is a rear elevational view of an electric meat, fish and bone cutter, embodying my new design;

Fig. 2 is a front elevational view of the same;

Fig. 3 is a perspective view showing one side and the front of the same; and

Fig. 4 is a side elevational view thereof, the side shown being opposite the side shown in Fig. 3 and the carriage moved forwardly of the position in Fig. 3.

The dominant features of the design reside in the portions shown in full lines.

I claim:

The ornamental design for an electric meat, fish and bone cutter, substantially as shown and described.

ARNOLD C. SCHUEREN.
